Primary Examiner — Natasha Vujcic(74) *Attorney, Agent, or Firm* — Leydig, Voit & Mayer Ltd(57) **CLAIM**

The ornamental design for a seat cushion, as shown and described.

DESCRIPTION

FIG. 1 is a front top isometric view of a second embodiment of my new seat cushion design;

FIG. 2 is a rear bottom isometric view thereof;

FIG. 3 is a front view thereof;

FIG. 4 is a rear view thereof;

FIG. 5 is a right side view thereof;

FIG. 6 is a left side view thereof;

FIG. 7 is a cross-sectional view taken along line 7-7 of FIG. 3;

FIG. 8 is a top plan view thereof; and,

FIG. 9 is a bottom plan view thereof.

The broken dash line hatching shown in the cross sectional drawing view of FIG. 7 forms no part of the claimed invention. The broken dash lines shown in the drawing views represent non-claimed subject matter and form no part of the claimed invention.
